UNITED STATES PATENT OFFICE.

JOHN GALBRAITH, OF ST. PAUL, MINNESOTA.

SANDING MACHINE.

Application filed April 23, 1921. Serial No. 464,056.

To all whom it may concern:

Be it known that I, JOHN GALBRAITH, a citizen of the United States, resident of St. Paul, county of Ramsey, State of Minnesota, 5 have invented certain new and useful Improvements in Sanding Machines, of which the following is a specification.

The object of my invention is to provide an improved form of guide bar for the 10 sanding head or shoe to the end that the movement of the shoe or head may be more uniform and even.

A further object is to provide an improved form of drive, and means for regulating 15 the stroke or travel.

Other objects of the invention will appear from the following detailed description.

In the accompanying drawings forming part of this specification,

20 Figure 1 is a side elevation of a sanding machine embodying my invention;

Figure 2 is a plan view of the same;

25 Figure 3 is a detail view of a portion of the machine, showing the mechanism for adjusting the length of the stroke;

Figure 4 is a sectional view on the line 4-4 of Figure 3;

Figure 5 is a sectional view on the line 5-5 of Figure 4;

30 Figure 6 is a transverse sectional view showing the construction of the guide bar;

Figure 7 is a view on the section line 7-7 of Figure 6;

Figure 8 is a sectional view on the line 35 8-8 of Figure 4;

Figure 9 is a side view of the guide bar and the mechanism for raising and lowering it;

Figure 10 is a sectional view on the line 40 10-10 of Figure 9;

Figure 11 is a sectional view showing the means for raising and lowering the work-supporting table;

Figure 12 is a sectional view on the line 45 12-12 of Figure 11;

Figure 13 is a transverse sectional view showing the lever for raising and lowering the guide bar;

Figure 14 is a sectional view on the line 50 14-14 of Figure 2.

In the drawing, 2 represents the frame of the machine, in which the sanding mechanism is mounted. At one end of the machine is a drive shaft 3 having at one end 55 fixed and loose pulleys 4 and 5 and at the

other end a pulley 6. At the opposite end of the machine is a driven shaft 7 having a pulley 8 secured thereon. A sanding belt 9 passes around these pulleys and its upper run, as shown in Figure 1, is engaged at 60 one end of the machine by a suitable belt tightener 10. The lower run of the sanding belt travels over a horizontal work supporting table 11 that is supported to move transversely with respect to the belt on rails 12 carried by the frame of the machine, the table having suitable anti-friction rollers 13 to rest and roll upon these rails, as usual in machines of this kind. The rails are supported by upright screws 14 journaled 70 in the machine frame and the upper ends of these screws are geared to a horizontal shaft 15 having an operating crank 16 by means of which the screws may be revolved and the table and the supporting rails raised 75 and lowered in the machine frame to adapt the machine for pieces of work of different sizes and shapes. All this mechanism is of ordinary construction in machines of this type. 80

A driving belt 17 connects the drive shaft 3 with a pulley 18 on a shaft 19 that is journaled in the machine frame and has a belt connection 20 with a pulley 21 loosely mounted on a sleeve 22 that is journaled in 85 bearings in the machine frame. The pulley 21 has a clutch member 24 secured to the hub thereof and a clutch member 24^a is secured to the sleeve 22 by suitable means, such as a set screw 26, and carries clutch wings 27 90 pivoted at 28 and adapted to engage an internal friction surface on the clutch member 24, being normally held out of contact with said surface by the tension of a spring 29. A bar 30 is mounted in the clutch member 24^a and has one end projecting between the wings 27 in position to separate these wings and cause them to engage the internal friction surface of the clutch member 24 when the clutch member 25 which is slidably 100 mounted on sleeve 22 is operated.

A rod 31 is connected with the clutch member 25 and is provided with a crank arm 32 to which the operating bar 33 is attached and adapted for movement longitudinally to oscillate the arm 32, rock the rod 31 and shift the clutch to lock or release the pulley 21. The bar 33 projects horizontally to a position where it can be conveniently reached by the operator of the 110

machine and easily manipulated to set or release the clutch.

One end of the sleeve 22 is provided with a head 34 and a screw 35 is mounted therein 5 and carries a block 36. A shaft 37 is mounted in the sleeve 22 and is geared at 38 to one end of the screw 35, said shaft having an operating crank 39 by means of which the attendant may revolve the shaft 37 and the 10 screw 35 and move the block 36 back and forth on the screw to change its position with respect to the longitudinal axis of the supporting sleeve and regulate the stroke of the pitman connected therewith. 40 is a 15 pitman rod mounted at one end on the block 36 and having a fork 41 at its opposite end that is pivotally connected at 42 with a quadrant 43 mounted to rock on a pivot 44. The teeth of the quadrant engage a pinion 20 45 on a shaft 46 to which a sheave 47 is secured. A cable 48 engages this sheave, passes around smaller sheaves 49 at each end of the machine and forms an endless belt connection for operating the sanding head 25 or shoe. The position of the sheaves 49 is indicated in Figure 6, where one of them is shown supported by a bracket 50 secured to the machine frame.

The sanding head, referring to Figures 6 30 and 7, comprises a frame 51 having a universal joint portion 52 whereon the shoe 53 which engages the sanding belt is mounted. Brackets 54 are mounted on the frame 51 and anti-friction bearings such as wheels 35 55 and 56 are supported in said brackets in planes substantially at right angles to each other. A clamp device 51^a is provided at each end of the frame 51 for connecting it with the operating cable 48, so that the rocking 40 of the sheave 47 and the forward and backward movement of the cable 48 will be transmitted to the sanding head and shoe and through the shoe and the sanding belt to the surface of the work.

45 I provide an improved form of guide bar in connection with this head and shoe, consisting preferably of upper and lower members or bars 57 and 57^a held in parallel relation by blocks 58 interposed between them. 50 The anti-friction bearings 55 operate on the opposing inner faces of the bars 57 and 57^a and the bearings 56 operate on the longitudinal edges of the lower bar 57^a, and thereby the shoe frame is held and guided 55 with an even uniform stroke throughout its movement.

The pressure of the sanding belt is varied by the vertical adjustment of the guide bar 57 and this I prefer to accomplish by providing shafts 59 mounted in the machine frame at one end and having hubs 59^a thereon provided with depending arms 60 connected by a bar 61 to insure uniform stroke of the arms. Arms 62 are secured to the 65 shaft 59 and links 63 are pivotally connected

with the ends of said arms 62 and are also pivotally connected with links 64 which are mounted at the lower end on the guide bar 57 and pivotally connected at their opposite ends with arms 65 that are mounted on the 70 hubs 59^a, thus completing a parallel link movement which will insure a vertical stroke of the guide bar instead of an oscillating one. A strap 66 is mounted on the middle portion of the guide bar and is slidably connected by means of a slot 67 and pin 68 with a lever 69 that is mounted at one end on the machine frame and has a hand grip 70 at its opposite end to be grasped by the operator for depressing or raising the guide 75 bar. The lever 69 also preferably has a slot 71 to receive a guide pin 72 on a bracket 73, said pin and slot serving to guide the lever in its movement and enable the attendant to apply the pressure of the guide bar 80 at the desired point on the sanding belt.

When the clutch is thrown out of engagement, the momentum of the sanding head is checked by a brake on the sheave 47, as illustrated in Figure 2, wherein a bar 74 is 90 pivoted at 75 to the machine frame. When the clutch operating bar 33 is pulled toward the operator to release the clutch, the cross bar 76, pivoted on the clutch operating bar 33 and bar 74 will force the block 77 into 95 frictional engagement with the sheave 47, thus checking movement of the cable and sanding head.

In the operation of the machine, the attendant drawing the table to its outer position, will place the work thereon, having previously adjusted the table to the desired elevation, then will push the table and the work in under the sanding belt and grasping the pressure lever, will apply the desired 100 pressure to the sanding shoe, which in turn will transmit it through the belt to the surface of the work. At any time during the progress of the work the stroke or travel of the head may be varied by the adjustment of the block connecting the pitman rod 105 with its operating mechanism. The guide bar comprising as described, the upper and lower portions with the frame of the sanding or pressure shoe mounted between them, 110 insures even, uniform travel of the shoe and an equal pressure at all points on the sanding belt.

I claim as my invention:

1. In a sanding machine, a guide bar comprising flat upper and lower plates arranged in parallel relation and spaced apart and means at intervals securing the middle portions of said plates together, an unobstructed passage being provided between 120 said plates upon each side of said securing means, a sanding head arranged beneath the lower member of said guide bar and having anti-friction bearings on the longitudinal edges of said lower member, and 125

similar bearings between said members, and a sanding shoe connected with said head.

2. In a sanding machine, a guide bar comprising upper and lower members spaced apart and secured together in parallel relation, a sanding head having brackets arranged to straddle said guide bar and bearings carried by said brackets and fitting 10 between the upper and lower members of said bar to slide thereon, and a shoe connected with said sanding head.

3. The combination, with a guide bar having upper and lower sections, of a sanding head comprising a frame extending transversely of said bar and beneath the same and having upwardly projecting brackets, anti-friction wheels mounted in said frame to bear on the longitudinal edges 20 of said bar and similar wheels mounted in said brackets in planes at right angles substantially to the other wheels and fitting between the upper and lower sections of said bar.

25 4. In a sanding machine, a guide bar composed of upper and lower members having opposing guiding surfaces, a sanding head comprising a frame having bearing on the longitudinal edges of one of said 30 guide bar members and also having brackets to straddle said guide bar, said brackets having bearing on the opposing inner sur-

faces of said guide bar members, and a sanding shoe connected with said frame.

5. In a machine of the class described, a 35 guide bar comprising upper and lower members spaced apart and secured together in parallel relation and having opposing guiding surfaces, a sanding head extending transversely of said bar beneath the same 40 and having upwardly projecting members bearing on the opposing guiding surfaces, and means mounted on said head and bearing on the longitudinal edges of one of said members for holding said head against lateral movement.

6. The combination, with a guide bar having upper and lower members provided with opposing guiding surfaces, of a head having anti-friction bearings on said opposing surfaces, said head also having bearings on a 50 longitudinal edge of said guide bar.

7. A guide-bar comprising upper and lower members spaced apart and secured together in parallel relation and having opposing guiding surfaces, a head having means fitting between the upper and lower members of said bar and having anti-friction bearings on said surfaces, and a shoe connected with said head.

In witness whereof, I have hereunto set my hand this 18th day of April, 1921.

JOHN GALBRAITH.
